UNITED STATES PATENT OFFICE

2,468,942

X-RAY TUBE COOLING APPARATUS

Wijbe Johannes Oosterkamp and Antonius Wilhelmus Vingerhoets, Eindhoven, Netherlands, assignors to Hartford National Bank and Trust Company, Hartford, Conn., as trustee

Application July 1, 1946, Serial No. 680,612
In the Netherlands March 15, 1943

Section 1, Public Law 690, August 8, 1946
Patent expires March 15, 1963

6 Claims. (Cl. 250—143)

1

The load which an X-ray tube can withstand for a comparatively long time is a function of the amount of heat carried off per unit of time. For testing materials and for the investigation of technical constructions tubes are of importance which can remain operative for the duration of the investigation, which in most cases extends over a few minutes but which in some cases may last much longer. With times of load of this order of magnitude, the distribution of heat in the anode is stationary, that is to say independent of time and hence solely dependent upon the dimensions and the coefficients of thermal conductivity of the materials used.

If the load is given a sufficiently low value, an ordinary technical X-ray tube may be used for these investigations. In this case, however, the possibilities of application are very small and are limited to investigations of thin layers of material and thin-walled constructional parts. According as the thickness of the objects to be investigated increases, the tube must be capable of withstanding a higher load. A comparatively high load is permissible with such tubes, it is true, if the surface of impact of the electrons on the anode is given a larger size and the larger amount of heat thus produced in the anode can be carried away by the cooling system. As a result of the large focus, the images obtained are highly unsharp and this is detrimental to the accuracy of the investigation. Applicant has found that the known constructions comprising an anode which radiates heat at high temperature, and those comprising an anode having a high heat capacity, which is cooled by liquid, or of which the anode is in intimate thermal relation with a body having a large heat-radiating surface, cannot satisfy the requirements imposed for the said purpose as regards quality of image and load capacity.

In order to increase the load continuously permissible, an X-ray tube is already known which comprises a disc-shaped anode constituted by a thin metal plate, the heat produced in this plate as a result of the impact of electrons being carried away on the side which is remote from the surface of impact. In this case the disc-shaped anode must be cooled very thoroughly since the surface available for the transmission of heat is much smaller than in the first-mentioned constructions. Thus the back of the anode plate is cooled with the aid of a liquid flow, the liquid being conducted with great speed along the surface. For the speed of the liquid it is decisive that the flowing must be turbulent, it being neces-

sary that between the turbulent core and the contact surface there should be a layer in which the flowing is laminar. Consequently, the evacuation of heat takes place in two stages:

- 5 (1) By conduction by the laminar limiting layer
(2) By convection in the turbulent core of the flow.

10 A good conduction of heat by the laminar limiting layer may be obtained by utilizing a liquid having a high thermal conductivity. For the second factor the specific heat per unit of volume and the speed of the liquid are the principal characterizing magnitudes. The speed of the liquid flow is limited by the height of the pressure, which is related to the section of the conductors and the viscosity of the liquid.

15 This invention relates to an X-ray tube comprising an anode, the surface of impact of the electrons being constituted by a thin metal plate and the heat produced in the latter being carried away on the side which is remote from the surface struck by the electrons.

20 The present invention purports to improve the evacuation of heat of this tube in such manner that it can be loaded very strongly.

25 According to the invention, that side of the anode from which the heat is carried off is brought into intimate thermal relation with a cooling body the surface of which streaks along the anode, the intimate thermal relation between the anode and the cooling body being effected by a thin layer of a liquid having a great thermal conductivity. The transmission of heat

30 from the anode to the cooling body is better, according as the coefficient of thermal conductivity of the material between the two surfaces has a higher value. Materials serviceable for this purpose are liquid metals or metal alloys such, for

35 example, as mercury.

35 The heat produced in the anode is absorbed by the cooling body and must be carried off therefrom since with an increase in temperature the amount of heat absorbed by this body becomes

40 smaller and smaller. This evacuation of heat from the cooling body may be effected in different manners. The body may be arranged, for example, in the open air, so that it can emit its heat to the surroundings by means of radiation,

45 conduction and convection. The cooling body may alternatively be arranged in a housing, of which the wall serves as a heat-radiating member and which may be provided with cooling ribs for the purpose of enlarging the radiating surface, or

50 be cooled artificially. An advantageous form of

construction is obtained if the space which exists between the cooling body and the housing is filled with a liquid similar to that which is present between the anode and the cooling body, so that this liquid also serves for the transmission of heat from this body to the wall of the housing. It is advisable that use should be made of a cooling body consisting of metal having a high thermal conductivity such, for example, as copper, and a high heat capacity. The advantage thereof is that the heat which is quickly distributed in the body, due to which the heat emission takes place over as large a surface as possible and the variation in temperature in the cooling liquid may be small.

In many cases the focal spot, that is the spot of the anode which is struck by electrons will have an elongated shape, the longest dimension of which as viewed in the direction of the emanating X-ray beam is observed as shortened. In this case it is advantageous for a good transmission of heat from the anode to the cooling body if the direction of motion of that surface of this body which streaks along the anode is at right angles to the longest dimension of the spot of impact of the electrons.

The cooling body is preferably realized as a rotary member and is given the shape of a cylinder or a disc. The cooling of this member may alternatively be effected by a separate liquid, for example by making the cooling body hollow and by supplying and carrying off the cooling liquid through the axis of rotation.

The invention will be explained more fully by reference to the accompanying drawing showing, by way of example, one form of construction of a tube according thereto.

X-ray tube 1 comprises a cooling device 2 and is constituted by a metal portion 3 provided with an aperture 4 closed by a thin metal plate 5 of tungsten. This metal plate, which constitutes the anode, serves as the disc of impact for the electrons and is heated under the action of the impact of electrons. The heat produced in the disc is carried away at its back and is transmitted to a cooling body 8 by means of a liquid which completely fills the casing 6 of cooling device 2 and which is also present between anode 5 and cooling body 8. The presence of this liquid is not sufficient quickly to carry off the heat from the heated surface, although in the example shown the whole heat transport is effected via the liquid. The heat is emitted by the liquid to the wall of casing 6 which comprises cooling ribs 7 to facilitate the radiation of heat to the surrounding air. The emission of heat may be increased by means of artificial cooling of casing 6, for which purpose it may be provided with an envelope, a liquid or a gaseous cooling agent being led through the space which exists between the casing and the envelope.

Cooling body 8, which is preferably of copper, is shaped in the form of a disc and can rotate about a shaft 9 which is led to the exterior through the wall of casing 6 of the cooling device with the aid of an obturating ring 10 for the liquid. When the X-ray tube is operative, disc 8 is rotated; shaft 9 may be driven by means of a motor which may be united to form one whole with the cooling device. The number of revolutions of disc 8 may be, for example, 50 per second.

Due to the fact that a continuously changing part of the conical surface of cooling body 8 is opposite the anode, the heat is rapidly carried away from the latter and absorbed by the cool-

ing body. The heat absorbed by this body is retransmitted, by means of the liquid present in the casing, to the wall of the casing, which comprises cooling ribs 7 for the purpose of facilitating the emission of heat to the surroundings.

It is advisable that the metal member 8 should be arranged in such manner that between its surface and the heated surface of the disc of impact there exists only a small intermediate space so that at this place exists a thin layer of the liquid. The conditions for the obtainment of the highest possible increase in load relatively to the known tubes are best satisfied if this spacing is as small as possible and, for example, so small that the surface of the metal member does not contact with the surface of the disc of impact in the case of flection of the latter due to heating by electrons. The difference of temperature in the thin liquid layer may consequently be very small.

The metal portion 3 of the X-ray tube is connected to a glass portion 11 of the wall, comprising a re-entrant part 12. The latter carries a collecting device 13 containing an incandescent cathode 14 which is heated by electric current, for which purpose serve supply conductors 15 and 16 which are led in a vacuum-tight manner through the glass stem 17.

The cooling device may be fastened to the tube by means of a flanged connection 18, for which purpose the extremity of the metal portion 3 of the tube has a larger wall thickness. Consequently, the tube may be completely finished and exhausted before the arrangement of the cooling device.

Portion 3 of the wall is provided with an aperture 22 which is closed by a thin glass window serving for the transmission of active rays.

Several other constructions of the cooling system are possible, for which also use is made of the invention, so that the inventive idea is by no means limited to the form of construction shown in the figure.

What we claim is:

- 45 1. An X-ray tube, particularly adapted for prolonged loads, comprising a cathode, an anode comprising a target heated on the surface facing the cathode by electrons from the cathode, and to be cooled by removal of the heat through the rear surface thereof; and means for cooling the anode by rapid removal of the heat therefrom, said means including a body of liquid having a high thermal conductivity in intimate thermal contact with the rear surface of the anode, and a rotatable disc-shaped cooling body disposed so its peripheral edge is immersed in the liquid and closely adjacent the rear surface of the anode plate and separated therefrom by a film of the liquid.
- 50 2. An X-ray tube as in claim 1, in which mercury is used as the liquid to transmit heat from the anode to the cooling body.
- 55 3. An X-ray tube as in claim 1, in which the heat transfer liquid and the cooling body are enclosed in a vessel having heat-radiating surfaces, and the heat transfer liquid engages a substantial area of the inner surface of the vessel to conduct heat thereto for dissipation from the outer surface of the vessel.
- 60 4. An X-ray tube as in claim 1, in which the anode plate is at an angle to the cathode and the electron beam impinges on the target to form a line focus having an axis in a given direction, and the direction of motion of the cooling body is at right angles to said axis of the electron spot.

5. An X-ray tube as in claim 1, in which the heat transfer liquid and the cooling body are enclosed in a vessel, and the rotatable cooling body is mounted on a rotatable shaft extending through a wall of the vessel.

6. An X-ray tube as in claim 1, in which the anode plate has a given thermal mass, and the cooling body has a substantially greater thermal mass than the given thermal mass of said anode.
